UNITED STATES PATENT OFFICE.

WILLIAM J. WRIGHT, OF PITTSBURG, PENNSYLVANIA, ASSIGNOR OF THREE-SIXTEENTHS TO J. W. LEE AND FRED J. GALLOWAY, OF PITTSBURG, PENNSYLVANIA.

EXPLOSIVE-ENGINE.

SPECIFICATION forming part of Letters Patent No. 742,143, dated October 20, 1903.

Application filed February 11, 1902. Serial No. 93,487. (No model.)

To all whom it may concern:

Be it known that I, WILLIAM J. WRIGHT, residing at Pittsburg, in the county of Allegheny and State of Pennsylvania, have invented a new and Improved Explosive-Engine, of which the following is a specification.

My present invention seeks to provide an improved type of explosive-engine of a very simple and inexpensive construction in which the several parts are combined and co-operatively held to effect a positive and uniform operation with a minimum charge of working agent and in such manner that a maximum impelling force is obtained at each explosion.

In its generic nature my present invention comprehends a new correlation of a single working cylinder, a single pumping-cylinder, and valved connections for joining both ends of the working and pumping cylinders, said parts being arranged and combined, whereby as the working piston completes one cycle of its movement to compress and explode a new charge of the working agent the pumping means will force out the exploded mixture back of the piston and at the same time blow a new charge into that end from which the burned charge is expelled.

My invention also includes in its complete make-up a peculiar and novel construction of working cylinder, pump-cylinder, and co-operating pumping and working pistons and valved feedways for joining the ends of the two cylinders, having especially for its purpose to provide for utilizing the working piston for compressing the working-agent charge only and for uncovering and recovering the exhausts as the new charge is blown into the working cylinder by pump action.

Again, my invention has for its object to provide in an engine of the character stated a working cylinder having a valved working-agent intake at each end, centrally-disposed exhausts, a piston adapted to uncover and recover said exhausts, and means for feeding the new charge under a low pressure, whereby to relieve the working piston from an excess retarding force during its return or compressing movement; and in its more subordinate features my invention consists in certain novel details of construction and pecu-

liar combination of parts, all of which will hereinafter be fully described, and specifically pointed out in the appended claims, reference being had to the accompanying drawings, in which—

Figure 1 is a perspective view of my improved engine. Fig. 2 is a vertical longitudinal section of the same, taken practically on the line 2 2 of Fig. 4. Fig. 3 is a horizontal section of the same, taken on the line 3 3 of Fig. 2. Fig. 4 is a top plan view of the same, one end being broken away. Fig. 5 is a cross-section taken on the line 5 5 of Fig. 2. Fig. 6 is a plan view of the crank-shaft end of the machine. Figs. 7 and 8 are diagrams illustrating the variable or independent shifting of the pump and working pistons and means for coupling them to reciprocate in unison.

In the practical construction of my invention the same comprises a suitable base or bed frame 1, having flanges 1^a for conveniently and firmly securing said bed upon a floor or other foundation, as clearly shown in Figs. 1 and 2, by reference to which it will also be seen the upper surfaces of the two side portions 1^b 1^b of the frame have slideways 2 2 for the cross-head 3, presently again referred to, and at the outer or rear end said frame 1 has a laterally-extended portion 1^x, upon which the drive-shaft bearing 4^x is mounted. The shaft 4 at its outer end carries a fly-wheel 5, and upon the inner end thereof is fixedly held a disk 6, having a crank or wrist pin 6^b. If desired, the disk 6 may be omitted and the inner end of the shaft formed with the usual crank portion.

7 designates the working cylinder closed at both ends, the inner one, 7^a, of which has a suitable gland and stuffing-box 7^b for the rod 8^a of the working piston 8, and the said inner end 7^a has a flange 7^c for conveniently and firmly connecting with a similar flange 1^c on the front end of the frame 1. The working cylinder 7 has the usual water or cooling jacket 7^d, provided in the practical arrangement of my invention with the usual water intake and offtake pipes.

9 designates the pumping-cylinder, which to provide for economy in manufacture and convenience in assemblage of the several

parts is also disposed in a horizontal plane and supported upon the working cylinder, as clearly shown in the drawings. The cylinder 9 has a feed-port 9^a at each end, and the 5 said ports communicate with a single working-agent collecting-chamber 10, detachably mounted on the pump-cylinder 9, and the said ports 9^a 9^a are normally closed by the automatically-closing (spring-held) valves 9^x 9^x, 10 that seat within the chamber 10 and to which access may be readily had by removing the cap-plates 11 11, that cover the manholes 11^a 11^a, one over each valve 9^x. (See Fig. 2.) The 15 chamber 10 has a central feed-opening 10^c, which connects with a mixing mechanism 12, controlled by governor devices 12^a of any approved construction, which serve to feed the charge into the chamber 10 proportionate to the speed or acquired power desired for the 20 engine, and as the said governor means and mixing devices may be of any approved construction and form, *per se*, no part of my present invention further description thereof is deemed unnecessary.

25 The working cylinder has a feed-port 17 17^a at each end, and centrally it has a pair of exhausts 13 13^a in close relation discharging into an offtake 13^x common to both exhausts. Coöperating with each feed-port 17 17^a is an 30 automatically (spring-held) valve 14 14, to which access may be had through the capped openings 15 15 in the ends of the two conveying-tubes 16 16^a, that connect the exhausts 9^c 9^c of the pump-cylinder, and for reasons pres- 35 ently explained the exhaust 16 at one end of the cylinder 7 crosses over and communicates through the valved port 17 at the opposite end of the working cylinder, and exhaust 16^a likewise crosses over and communicates with 40 the inlet-port 17^a of the working cylinder.

So far as described my improved engine mechanism in its coöoperative action provides for blowing out a burned charge back of the working piston and feeding in a new charge 45 back of the said working piston as a prior charge is being compressed and exploded and in such manner that the working piston, except as presently explained, serves no other function than that of compressing the charge 50 ahead of it, as it in no way acts to draw in a new charge behind it, as that operation is effected by the pump. It should be stated, however, that the working piston, the relative sizes of said working piston, and the 55 working cylinder and the exhausts thereof are such that in its compression action in opposite directions the working piston will uncover alternately the exhausts at predetermined times, as will presently be made more 60 clear.

By referring now more particularly to Fig. 2 it will be noticed the pump-piston 18 has its rod 18^a guided in a standard 19, connected to the cross-head 3 and pivotally joined, 65 as at 18^b, to the upper end of the member 20^a of a bell-crank lever 20, the other member 20^b of which in my construction of engine forms

the pitman that connects the cross-head 3 with the wrist-pin or crank member 6^a of the drive-shaft, and the said lever 20 at its angle 70 is fulerumed to the cross-head, as designated by 20^x in Fig. 2. By thus joining the piston-rods of the working and pumping pistons it is manifest that the two pistons are made to reciprocate in like directions in unison, and 75 by reason of the crossover connection of the ends of the two cylinders the pump-piston will be drawing into its coacting cylinder a new charge of working agent back of said pump-piston as it (the piston) is forcing a 80 charge of working agent in front of it into the working cylinder back of the working piston.

To more clearly illustrate the working of my engine so far as described, it is assumed 85 that the working piston has just reached its limit of the stroke in the direction indicated by the arrow and the charge in front is just ready to explode. When in such position, the burned mixture back of the piston being 90 the residuum of the prior charge will have been blown out of the exhaust 13^a and the chamber back of the said working piston (the right-hand end of the working cylinder) 95 filled with a new charge of the working agent, forced therein from the left-hand end of the pump-cylinder by the pump-piston. At this point it should be stated that while the pump and working pistons during the major part 100 of their reciprocal movements travel in unison in the same direction they also move differentially—that is, the pumping-piston has a greater length of stroke than the working piston, and this increase of stroke of the pumping-piston is provided for by pivotally connecting it to the bell-crank pitman member 20, which in turn is fulerumed at its angle 105 to the cross-head. The object in providing for this differential movement of the two pistons is to relieve the back of the working 110 piston from a too great retarding pressure as it begins to return to its compression-stroke of movement and to force the explosive-mixture charge into the working cylinder 115 with as little compression as possible, in practice but little above atmosphere. The differential movement of the stroke of the two pistons is best explained as follows: Assuming the working piston 8 in its movement in 120 the direction indicated by the arrow *x* to have just reached the point where its rear edge 8^x is beginning to uncover the exhaust 13^a, (see dotted line *a*,) at this time the axial point of the wrist or crank pin will be at the point indicated by *b* (see diagram Fig. 7) and the 125 rear edge of the pump-piston at the point indicated by dotted line *c* in Fig. 2. As the crank or wrist pin 6^a passes from the point *b* to the point *d*, which designates the full limit of the stroke of the piston 8 in the direction 130 indicated, the pump-piston will also be moved forward. It will, however, be noticed that while the working piston under the conditions stated is nearly to the finish of its stroke

the pump-piston is but little more than midway the length of its stroke, and hence has effected a very slight compression of the working charge in front of it, and by reason thereof it is manifest that as the piston 8 begins to uncover the exhaust 13^a the slightly-compressed new charge in front of the pump-piston will be forced out through the pump-cylinder exhaust 9^c, down exhaust-tube 16, through the valved opening 15 at the inner (right-hand) end of the working cylinder, the valve 14 opening under said pressure, and the said new charge will then blow any of the remaining prior-exploded charge through the exhaust 13^c. During this action the piston 8 reaches its limit, and the piston 18 slightly increases the compression of the charge before it as it draws in a new charge through the valved port 9^a back of it. The charge in front of the piston 8 being then exploded and the said piston 8 having a very slight back or retarding pressure, it (the piston) is quickly and under a great impelling force moved in the opposite direction and in doing so instantaneously recovers the exhaust 13^a. As the piston 8 is forced back by the explosive force in front of it and during the passing of the crank-pin from the point *d* to the point *e* (see Fig. 2) by reason of the rocking action of the lever member 20 the pump-piston will be shifted to the limit of its stroke forward to effect its greatest compression action on the charge still in front of it, which by reason of the then maximum force under which it is now expelled from the pump-cylinder will still pass by the valve 14 in the opening 15, before referred to. As the crank or wrist pin passes from the point *e* in the direction of the arrow, Fig. 2, the pump-piston will then move backward with the now backwardly-moving piston 8 to effect the same operations at the other ends of the pump and working cylinders, it being understood that in said back movement a new charge is being drawn into the cylinder 9 through the port 9^a at the left as the prior charge back of the piston 18 under a low compression is being forced through the outlet 9^c into the tube 16 and through the valved port 17 at the left-hand end of the cylinder 7, it being also understood that the exploded charge or residuum therein escapes through the exhaust 13 when piston 8 uncovers it.

From the foregoing description, taken in connection with the accompanying drawings, it is thought the complete operation of my invention and its advantages will be apparent to those skilled in the art to which it appertains.

It will be observed that by reason of the correlative arrangement of the several parts I am enabled to assemble them in a very compact, stable, and economical manner and to make the connections between the pump and working cylinders and the pistons such as to attain the maximum efficiency in durability and positiveness of action, and by having the

pump arranged to force the new charge into the working cylinder under a low pressure a more perfect equilibrium of the parts is acquired and a maximum impelling force obtained from each charge, and by forcing the new charge into the working cylinder in the manner stated it is possible to blow out the burned mixture with practically no waste of the new charge, thereby reducing the fuel cost for running the engine to the maximum.

One of the most advantageous features of my invention is that I dispense with the use of cams, eccentrics, gears, trip devices, &c., such as are commonly used for shifting the valve mechanism in explosive-engines, and by reason thereof I am enabled to produce an engine of very few parts, in which very little fine or expensive lathework will be necessary, and in which valve devices of a most simple or ordinary construction can be employed and of that type not adapted to readily become broken or disorganized.

While the detailed arrangement of the several parts as described and illustrated show a preferred construction, I desire it understood the exact arrangement of the details may be varied or modified without departing from the spirit of my invention or the scope of the appended claims.

Having thus described my invention, what I claim, and desire to secure by Letters Patent, is—

1. In an engine of the character described, a working cylinder and the piston therefor, said cylinder having a valved intake at each end, and a plurality of exhausts intermediate the intakes one for each of said intakes, a pump comprising a cylinder having a valved intake and an exhaust at each end, a feed communicating with both intakes, a conveying-tube for each pump-cylinder exhaust, the pump-piston and mechanism for joining the pump-piston with the working piston to move the two in unison during a part of their strokes, said mechanism including devices for imparting differential movement to the pistons during another portion of their strokes, for the purposes specified.

2. An explosive-engine of the character described, comprising the following elements in combination; a working cylinder having a valved intake at each end, and a plurality of centrally-disposed piston-controlled exhausts, one for each end of the cylinder, the working piston, a pump-cylinder having a valved intake and an exhaust at each end, the crossed tubes 16 16^a, for connecting said exhausts with the working-cylinder intakes, the pump-piston, and means for joining the pump-piston with the working piston, whereby the two pistons will be reciprocated in unison, said means including devices for continuing the thrust of the pump-piston in either direction as the working piston begins on its return movements, substantially as shown and for the purposes described.

3. The combination with the working cyl-

inder, its piston, and the cross-head, said cylinder having a valved intake at each end, and an exhaust in the center, the pump-cylinder having a valved intake and an exhaust at each 5 end, the pump-piston and the tubes 16 16^a, joining the exhausts of the pump-cylinder with the intakes of the working cylinder, and the crank-shaft, of the bell-crank member 20 pivotally mounted at its angle on the cross- 10 head, one of its arms being pivotally joined with the pump-piston rod, and the other with the crank or wrist pin of the crank-shaft, substantially as shown and for the purposes described.

15 4. The hereinbefore-described improved explosive-engine, comprising, in combination; a base or bed portion, a crank-shaft mounted in one end thereof, a cross-head slideable on the bed portion, a working cylinder secured 20 to the other end of the bed portion, and projected in a plane with the cross-head slide-way, said cylinder having a valved intake at each end, and exhausts 13 13^a centrally thereof, a pump-cylinder mounted on the working 25 cylinder, a valved intake and an exhaust in each end of the pump-cylinder, the tubes 16 16^a extended crosswise of the pump-cylinder, for connecting the pump-exhausts with the working-cylinder intakes, an automatic feed 30 for the pump, forming an attached part thereof, the pistons 8 and 18, the piston 8 having its rod 8^a pivotally joined to the cross-head, the bell-crank member 20, pivotally connected to the cross-head, and having one arm pivotally joined with the rod 18^a of the piston 18, 35 and the other arm joined to the crank or wrist pin of the crank-shaft, all being arranged substantially as shown and described.

5. An improved explosive-engine, compris-

ing a working cylinder and piston, said cylinder having a valved intake at each end and centrally-disposed exhausts, one for each end of the cylinder, means for feeding a new working charge into the said cylinder back of the piston, as the said cylinder uncovers 40 and recovers the exhausts, said means including a second cylinder and piston, said second cylinder arranged above the working cylinder, an exhaust at each end of the said second cylinder, the exhaust at one end of the second cylinder being connected to the inlet of the opposite end of the working cylinder, a drive-shaft, a bell-crank lever connecting the working-cylinder piston and the second-cylinder piston to the drive-shaft, all being 45 arranged substantially as shown and for the purposes described.

6. In an explosive-engine, a working cylinder and piston, said cylinder having a valved intake at each end and piston-controlled exhausts centrally arranged; a second cylinder and piston arranged above the working cylinder, valved intakes for said second cylinder, an exhaust for each end thereof, the exhaust of one end of the second cylinder being 50 connected to the intake at the opposite end of the working cylinder; a drive-shaft; a bell-crank connection between said working and second cylinder pistons and the drive-shaft whereby the pistons will move in unison 55 through a part of their stroke and whereby they will have a differential movement during the rest of the stroke for the purposes specified.
